LOADING MACHINE

Andrew Hauge, Claremont, N. H., assignor to
 Sullivan Machinery Company, a corporation of
 Massachusetts

Application June 20, 1931, Serial No. 545,669

8 Claims. (Cl. 198—8)

This invention relates to loading machines and more particularly, but not exclusively, to improvements in machines for loading coal or similar materials in mines.

5 An object of this invention is to provide an improved coal loading machine. Another object is to provide an improved coal loading machine of the track supported and guided type adapted to operate from the mine trackway.

10 A further object is to provide improved material gathering means for such a machine and improved means for driving the material gathering means. A still further object of this invention is to provide improved conveying means for such a machine. A still further object is to provide improved conveying means having associated therewith improved material gathering means and improved means for adjusting the conveying means relative to the main body of the machine to vary the loading position of the gathering means with respect to the material to be gathered and loaded thereby. Another object is to provide, in a machine of the above character, improved means for horizontally swinging the rear discharge conveyor and for vertically tilting the discharge end of the rear conveyor. A still further object is to provide an improved swivel mounting for the front and rear conveyors of such a machine.

25 These and other objects and advantages of the invention will, however, hereinafter more fully appear.

In the accompanying drawings there are shown for purposes of illustration one form and a modification thereof which the invention may assume in practice.

In these drawings,

Fig. 1 is a plan view of the illustrative embodiment of the improved loading machine.

40 Fig. 2 is a side elevational view of the machine shown in Fig. 1.

Fig. 3 is a horizontal sectional view taken substantially on line 3—3 of Fig. 2 and illustrating the transmission mechanism.

45 Fig. 4 is a detail side elevational view illustrating the control means for the transmission mechanism.

Fig. 5 is a plan view of the control means shown in Fig. 4.

50 Fig. 6 is a horizontal sectional view, with parts shown in plan, taken substantially on line 6—6 of Fig. 2.

Fig. 7 is a side elevational view of the mechanism shown in Fig. 6.

55 Fig. 8 is a transverse vertical sectional view

taken substantially on line 8—8 of Fig. 7, with parts omitted.

Fig. 9 is a horizontal sectional view taken substantially on line 9—9 of Fig. 7.

Fig. 10 is a detail sectional view taken substantially on line 10—10 of Fig. 7.

Fig. 11 is a transverse vertical sectional view taken on line 11—11 of Fig. 10.

Fig. 12 is a transverse sectional view, with parts shown in plan, taken substantially on line 10 5 12—12 of Fig. 2.

Fig. 13 is a longitudinally extending vertical sectional view taken substantially on line 13—13 of Fig. 12.

Fig. 14 is a horizontal sectional view illustrating the improved driving and swinging means for the rear conveyor, the section being taken substantially on line 14—14 of Fig. 15.

Fig. 15 is a side elevational view of the mechanism shown in Fig. 14.

20 Fig. 16 is a detail view taken substantially on line 16—16 of Fig. 15.

Fig. 17 is a fragmentary side elevational view of a modified form of the driving and swinging means for the rear conveyor and the power operated tilting means for the rear conveyor.

Fig. 18 is a horizontal sectional view taken substantially on line 18—18 of Fig. 17.

Fig. 19 is a transverse vertical sectional view taken substantially on line 19—19 of Fig. 18.

30 Figs. 20 and 21 are detail views illustrating the clutch control means.

Figs. 22 and 23 are detail views illustrating the control handle for the controlling clutches for the driving, swinging and tilting means for the rear conveyor.

35 Fig. 24 is a vertical sectional view taken substantially on line 24—24 of Fig. 19.

In this illustrative embodiment of the invention there is shown a coal loading machine of the track supported and guided type adapted to operate on the mine trackway and generally comprising a main frame or body 1 mounted through usual spring axle mountings on wheels 2 adapted to run along a mine trackway 3. 40 Mounted on the main frame 1 is a front elevating conveyor 4 and a rear discharge conveyor 5, and associated with the front elevating conveyor 4 is improved material gathering means generally designated 6. The front elevating conveyor 4 and its associated gathering mechanism 6 and the rear discharge conveyor 5 are mounted on the main frame of the machine for adjustment relative thereto in horizontal and vertical directions in an improved manner, as herein- 45 50 55

after described, and the front elevating conveyor and its associated gathering mechanism and the swinging and tilting means for the front conveyor are driven from a motor 7, while the driving and swinging means for the rear discharge conveyor are driven by a second motor 8. The transmission mechanism for driving the support wheels 2 is driven by a third motor 9. The gathering mechanism 6 gathers the material to be loaded and moves the material onto the shovel 10 of the front elevating conveyor 4. From this shovel the material is conveyed rearwardly by the front conveyor to discharge onto the rear discharge conveyor 5, the latter in turn discharging into a mine car placed beneath the discharge end of the rear conveyor in a manner well known to those skilled in the art. The support wheel driving transmission mechanism effects propulsion of the machine along the mine trackway during transport of the machine about the mine and during the loading operation.

Now referring to the support wheel driving means for propelling the machine along the mine trackway, it will be noted that the motor 9, which is herein preferably of the electric type, is arranged at the rear end of a frame 9^a with its power shaft 11 horizontally and transversely disposed. The frame 9^a is journaled at its opposite sides on the rear support wheel axle and is pivotally connected at 10^a to the main frame thereby forming a three point suspension for the frame 9^a. As shown in Fig. 3, fixed to one end of the motor power shaft is a sprocket 12 which drives, through a multiple chain connection 13, a sprocket 14 keyed to a horizontal shaft 15 extending transversely of and suitably journaled within the frame 9^a. As illustrated, forward feed of the machine is effected by a frictionally controlled planetary transmission mechanism comprising a spur gear 16 keyed to the shaft 15 and meshing with planet gears 17, 17 journaled on stub shafts 18 carried by a rotatable casing 19. Secured to a rotatable casing 20 is an internal gear 21 with which the planet gears 17 mesh, and the casing 19 is keyed to the hub of a chain sprocket 22. The rotatable casing 20 and sprocket 22 are suitably rotatably supported by the shaft 15, and the sprocket is connected by an endless chain 23 to a sprocket 24 fixed to the rear support wheel axle. The front and rear support wheel axles are connected in driving relation by a chain and sprocket connection 25, as shown in Fig. 1. The external periphery of the casing 20 is annularly grooved at 26 to form a friction braking surface with which a brake band 27 cooperates. It will thus be seen that when the casing 20 is held against rotation by the brake band 27, the support wheels may be driven at a transport speed from the motor 9 through the chain and sprocket connection 12, 13, 14, shaft 15, planetary gearing 16, 17, 21, rotatable casing 19 and the chain and sprocket connection 22, 23, 24. It will also be seen that by slipping the brake band 27, the speed of the support wheel drive may be reduced and that the speed may be regulated by the brake band 27 to effect drive of the support wheels at a loading speed. The reverse mechanism for driving the support wheels to propel the machine in the reverse direction comprises a spur gear 28 keyed to the shaft 15 and meshing with spur gears 29, 29 journaled on studs 30 carried by a rotatable member 31 rotatably supported by the shaft

15. The gears 29, 29 mesh with an internal gear 32 secured to a rotatable casing 33 keyed to the hub of the sprocket 22. The external periphery of the member 31 is annularly grooved at 34 to provide a friction braking surface for a brake band 35. It will thus be seen when the member 31 is held stationary by the brake band 35, the support wheels are driven in the reverse direction, at a slightly higher speed than the forward feed above described, through the gearing 28, 30, 32, rotatable casing 33 and chain and sprocket connection 22, 23, 24. This reverse speed may obviously be varied simply by slipping the brake band 35. To provide braking means for the support wheels, the rotatable casing 33 is annularly grooved at 36 on its external periphery to provide a friction braking surface with which a brake band 37 cooperates. When the brake band 37 is applied, the casing 33 is held against rotation, and since the casing 33 is connected directly to the support wheels through the chain and sprocket connection 22, 23, 24, rotation of the support wheels may be prevented.

The operating means for the brake bands 27, 35, 37 will now be described. As shown in Figs. 4 and 5, keyed to a transverse operating rod 38 is a double foot pedal 39. Also keyed to the rod 38 is a crank 40 connected through a pivoted link 41, in turn connected to one arm of a bell crank 42 pivotally mounted on a transverse rod 43, herein arranged parallel with and above the rod 38, as shown in Fig. 4. The other arm of the bell crank 42 is connected by a rod 44 to a lever 45 pivotally connected to the ends of the brake band 27. Also keyed to the rod 38 is a crank 46 connected by a pivoted link 47 to one arm of a bell crank 48 likewise pivotally mounted on the rod 43. The other arm of this bell crank is connected by a rod 49 to a similar lever pivotally connected to the ends of the brake band 35. As shown in Fig. 5, the bell cranks are made in two parts having relative movement, thereby forming a lost motion connection, and as a result, when one bell crank is turned to apply its brake band, the parts of the other bell crank move relatively to prevent excessive movement of its brake band toward released position. It will thus be seen that when the pedal 39 is pressed downwardly in one direction, the brake band 27 is applied while the brake band 35 is released, and when the pedal is pressed down in the opposite direction the brake band 27 is released and the brake band 35 is applied. The operating means for the support wheel brake comprises a lever 50 fixed to the rod 43 and operating a crank 51 also fixed to the rod, and this crank is connected by a brake rod 52 to a lever, similar to the lever 45, pivotally connected to the ends of the brake band 37. It will thus be seen that the machine may be propelled forwardly and rearwardly along the mine trackway under the control of the brake bands 27 and 35 and that the support wheels may be braked by suitable application of the brake band 37.

The front elevating conveyor 4 is driven from the motor 7 which is herein carried by the horizontally swingable frame 53 of the front conveyor, and the power shaft of this motor is herein horizontally and transversely disposed. Fixed to one end of the motor power shaft is a sprocket 54 connected by a multiple chain connection 55 to a sprocket 56 keyed to one end of a horizontal shaft 57 herein arranged parallel

with the motor shaft in advance of the latter and suitably journaled within the conveyor frame 53. Connected to the shaft 57 at its opposite end by a friction clutch 58 of a usual 5 design is a spur pinion 59, the friction clutch 58 being set at a predetermined load to slip automatically upon a predetermined load. The pinion 59 meshes with a spur gear 60 keyed to one end of a horizontal shaft 61 arranged parallel with and in advance of the shaft 57 and likewise suitably journaled within the conveyor frame 53. Keyed to the opposite end of the shaft 61 is a spur gear 62 meshing with a spur gear 63 keyed to a horizontal shaft 64 herein arranged parallel with and above the shaft 61, and likewise suitably journaled within the conveyor frame 53. Fixed to the shaft 64 adjacent the opposite ends thereof are sprockets 65, 66 which engage and drive the endless side chains 66, 66 of the front elevating conveyor 4. These side chains are mounted in suitable guideways formed in the conveyor frame 53 and in a vertically tilttable conveyor frame 67 pivotally connected at 68 to the forward portion of the conveyor frame 53, and these side chains are connected by transverse scraper bars 69 which slide along the bottom plates 70, 71 of the front and rear conveyor frames 67 and 53 respectively to move the material to be loaded, when the side chains are driven, along the bottom plates of the frames to discharge onto the rear conveyor 5 of the machine.

The improved gathering mechanism 6 comprises a pair of gathering devices 72, 73 and each of these devices consists of a frame member 74 having guided around its margin an endless gathering chain 75, the gathering chains moving in their orbits in planes parallel and adjacent to the inclined surface of the shovel 10 to move the material over the inclined shovel surface onto the front conveyor 4. Connected to each of the gathering chains 75 is a plurality of blocks 76, herein four, and pivotally mounted at 77 on each of these blocks is a holder 78 each having a rearwardly projecting arm 79 engaging the endless chain 75 in the manner shown in Fig. 12. Three of the holders 78 have formed therein sockets 80 to detachably receive gathering tools 81 held in position within the sockets by set screws 82, while the fourth holder has detachably secured thereto an upstanding pick member 83 for engaging and breaking down the material and dragging the material over the shovel 10 onto the front conveyor 4. The gathering devices 72, 73 are herein arranged at opposite sides of the shovel 10 in the manner shown in Fig. 1 and the gathering tools of the gathering devices swing outwardly, as the gathering chains move in their orbits, in advance of the shovel to dig into the material and sweep the material onto the shovel 10 in an improved manner. The means for driving the gathering devices herein comprises, as shown in Fig. 9, a spur gear 85 meshing with the spur gear 63 of the conveyor driving means, and this gear 85 is connectible by a sliding pin clutch 86 to a chain sprocket 87 keyed to one end of a horizontal shaft 88, this shaft herein arranged parallel with the shaft 64 with its axis coincident with the pivotal axis 68 of the tilttable frame 67 of the front conveyor. The pin clutch 86 is normally held in its connected position by a coiled spring 89 and for releasing the clutch there is provided a collar 90 with which a pivoted shipper yoke 91 cooperates. The shipper

yoke 91 is provided with a suitable operating handle 92. Referring to Figs. 6 and 9, keyed to the opposite end of the shaft 88 is a similar chain sprocket 93, and the chain sprockets 87 and 93 are connected through endless chains 94, 94 (see Fig. 12) to sprockets 95, 95 connected to and driving chain sprockets 96, 96. The sprockets 96, 96 are suitably rotatably mounted on horizontal shafts 97, 97 supported within the opposite sides of the tilttable conveyor frame 10 and are connected by endless chains, 98, 98 to sprockets 99 fixed to horizontal shafts 100. Fixed to the shafts 100 and driven thereby are bevel pinions 101 meshing with bevel gears 102 (see Fig. 13) keyed to shafts 103 herein arranged perpendicularly to the axes of the shafts 100 and suitably journaled within the conveyor frame 67. Keyed to the upper ends of the shafts 103 are sprockets 104 engaging and driving the endless gathering chains 75 of the gathering devices 72 and 73 respectively.

The mechanism for horizontally swinging the front elevating conveyor 4 relative to the main frame to vary the gathering position of the conveyor and its associated gathering mechanism comprises, as shown in Fig. 9, a spur gear 105 connectible to the shaft 61 by a multiple disc clutch 106. The gear 105 meshes with a spur gear 107 keyed to a horizontal shaft 108 arranged parallel with the shaft 57 and likewise journaled in the conveyor frame 53. Connectible to the shaft 108 by a jaw clutch 109 is a chain sprocket 110 which drives through an endless chain 111 a sprocket 112 fixed to a horizontal shaft 113. This shaft extends transversely of and is suitably journaled within the conveyor frame 53 and has fixed thereto a worm 114 meshing with the teeth of a worm gear segment 115 herein formed integral with an arcuate guide frame 116 attached to the forward portion of the machine frame 1. Carried by this guide frame are rollers 117 on which the overhanging end of the front conveyor is guided and supported. Also connectible to the shaft 61 by a multiple disc clutch 118 is a chain sprocket 119 connected by an endless chain 120 to a sprocket 121 fixed to the shaft 108. It will thus be seen that when the clutch 106 is applied, the front conveyor may be swung horizontally in one direction, and when the clutch 106 is released and the clutch 118 applied, the conveyor may be swung horizontally in the opposite direction. The clutch 109 is actuated by a shipper yoke 122 operated by a handle 123, while the friction clutches 105, 118 are operated by a clutch applying member 124 slidably mounted on the shaft 61 between the clutches. Engaging this shipper member is a shipper yoke 125 attached to a transversely extending operating rod 126. A lever 127 is provided for moving the operating rod 126 axially to shift the member 124 in opposite directions to apply one friction clutch or the other.

The pivotal mounting for the front conveyor about which the latter horizontally swings, comprises, as shown in Fig. 8, an annular swivel frame 129 rotatably mounted on a cylindrical bearing frame 130 suitably attached to the upper part of the machine frame 1. Secured to the annular swivel frame 129 at diametrically opposite points with respect to the pivot axis are pins 131, 131 to which the rear portion of the conveyor frame 53 is pivotally connected, and the pivotal connections of the conveyor frame with the pins permit a slight vertical tilting movement of the conveyor frame during hori-

zontal swinging thereof along the arcuate roller frame 116. The mechanism for swinging the tiltable frame 67 of the front conveyor 4 to vary the elevation of the gathering mechanism 6 herein comprises a sprocket 132 connectible to the shaft 108 by the jaw clutch 109, and this sprocket is connected by an endless chain 133 to a sprocket 134 keyed, as shown in Fig. 11, to a horizontal shaft 135 herein extending transversely of the conveyor frame 53 and suitably journaled thereon. Suitably fixed to this shaft adjacent the opposite ends thereof are worms 136, 136 meshing with worm wheels 137, 137 keyed to parallel shafts 138, 138 as shown in Fig. 10. These shafts are suitably journaled within the conveyor frame 53 and are threaded at 139 throughout a portion of their length. As shown, the threaded portions of the shaft 138 are threadedly connected at 140 within the end portions of a transverse cylindrical member 141. Pivotally connected to the member 141 is a link member 142 engaging a transverse rod 143 secured at its ends within the depending side arms of the tiltable conveyor frame 67. The projecting arms 144 of the link 142 are slotted at 145 to permit free upward rocking movement of the tiltable conveyor frame 67 relative to the link 142, so that when the forward end of the shovel and gathering mechanism engage some obstruction in their path of movement, the front conveyor frame is free to tilt upwardly to enable the shovel to pass over such obstruction. It will thus be seen that when the sprocket 132 is connected to the shaft 108 by the clutch 109, the screws 139 are rotated through the worm gearing 136, 137, and as a result the member 141 and link 142 are moved in one direction to effect tilting of the front conveyor frame in one direction. Rotation of the screws in the opposite direction to effect tilting of the front conveyor frame in the opposite direction is accomplished by suitably controlling the reverse frictions 106, 118. As previously mentioned, the rear discharge conveyor 5 is mounted for horizontal swinging movement and the pivotal mounting for the rear conveyor comprises, as shown in Fig. 8, a swivel frame 146 mounted on top of the cylindrical bearing frame 130 and having an annular flange 147 rotatably mounted in an annular groove 148 formed by an annular frame 149 secured to the top of the cylindrical bearing frame 130, as shown. The horizontally swingable frame 150 of the rear conveyor is pivotally connected at 151 to pins 152 arranged diametrically with respect to the pivotal axis on the rear conveyor and carried by the swivel frame 146. These pivotal connections permit a slight vertical tilting movement of the rear conveyor frame 150 during horizontal swinging thereof. The mechanism for driving the rear conveyor comprises the motor 8, which is herein preferably of the reversible electric type, arranged on the rear conveyor frame 150 with its power shaft horizontally and transversely disposed. The motor power shaft is connected by a friction clutch 153 of a usual design, which is set to slip upon a predetermined load, to a shaft 154. Fixed to the shaft 154 is a spur pinion 155 meshing with a spur gear 156 in turn fixed to a horizontal shaft 157 suitably journaled within the conveyor frame 150. Fixed to the shaft 157 is a spur gear 158 meshing with a spur gear 159 connectible by a jaw clutch 160 to a horizontal shaft 161. The clutch 160 is operated by a shipper yoke 162

having a suitable operating lever 163. Secured to the shaft 161 adjacent the opposite ends thereof are chain sprockets 164, 164 which engage and drive the endless side chains 165, 165 of the rear conveyor 5. The side chains of the rear conveyor are arranged in suitable guideways formed on the conveyor frame 150 and a vertically tiltable frame 166 of the rear conveyor, the latter being pivotally mounted at 167 on the rearward portion of the conveyor frame 150. Secured to the side chains of the rear conveyor are transverse scraper bars 168 which slide, when the side chains are driven, over the bottom plates 169, 169 of the conveyor frames 150, 166 to move the material towards discharge. The mechanism for horizontally swinging the rear conveyor herein comprises a chain sprocket 170 fixed to the shaft 157, as shown in Fig. 14, and connected by an endless chain 171 to a sprocket 172 journaled on a horizontal shaft 173 in turn journaled within the conveyor frame 150. The sprocket 172 is connectible to the shaft 173 by a jaw clutch 174 and keyed to the shaft 173 is a chain sprocket 175 connected by an endless chain 176 to a sprocket 177 fixed to a horizontal shaft 178. This shaft extends transversely of the rear conveyor frame 150 and is suitably journaled thereon and has fixed thereto intermediate its ends a worm 179 meshing with a worm wheel 180 fixed to a vertical shaft 181 suitably journaled within the conveyor frame 150. Fixed to the lower end of the shaft 181 is a spur pinion 182 meshing with an arcuate gear segment 183 formed on an arcuate frame 184 supporting rollers 185. It will thus be seen that when the clutch 174 is connected the rear conveyor may be swung horizontally in one direction and is guided during such horizontal swinging movement by the arcuate roller frame 184. To effect swinging of the rear conveyor in the reverse direction, there is provided a sprocket 186 engaging the lower strand of the chain 170 in the manner shown in Fig. 15, and this sprocket is journaled on a horizontal shaft 187 in turn suitably journaled within the conveyor frame 150, and is connectible to the shaft 187 by a jaw clutch 188. Fixed to the shaft 187 is a chain sprocket 189 connected by an endless chain 190 to a sprocket 191 fixed to the shaft 178. It will thus be seen that when the clutch 188 is connected, the shaft 178 of the swinging mechanism is driven in the reverse direction through the chain and sprocket connection 189, 190, 191. The clutches 174 and 188 are so co-ordinated that when one is connected the other is released and the operating means for these clutches consists, as shown in Figs. 14 and 16, of shipper yokes 192, 193 engaging the jaw clutches 174 and 188 respectively, and these shipper yokes are secured to vertical operating rods 194 and 195 respectively. Secured to the rod 195 is a lever 196 pivotally connected to a link 197 in turn pivotally connected to a control handle 198. Pivotally connected to the link 197 is a lever 199 secured to the operating rod 194. It will therefore be evident that when the handle 198 is swung outwardly, the link 197 is moved inwardly, swinging the levers 196, 199 about their pivots, and as a result, the shipper yokes 192, 193 are operated to connect the clutch 174 and release the clutch 188. When the handle 198 is swung in the opposite direction, the clutch 188 is connected and the clutch 174 is released. The mechanism for swinging the tiltable frame 166 of the rear conveyor 5 about its pivot

167 to vary the elevation of the discharge end of the rear conveyor herein comprises hand wheels 208, 209 arranged, as shown in Fig. 1, beneath the rear portion and at opposite sides 5 of the conveyor frame 150, and these hand wheels are fixed to the lower ends of vertical screws 201 suitably rotatably mounted within the opposite sides of the conveyor frame 150. These hand wheels and screws are connected 10 together by a chain and sprocket connection 202 so that either hand wheel may be rotated to operate the tilting mechanism. In the present construction, the screws are threadedly connected to non-rotatable nuts 203 secured to 15 a transverse angle member 204 which engages abutment members 205 attached to the sides of the tiltable frame 166. It will thus be seen that when the screws are rotated, the nuts 203 are moved axially, thereby moving the abutment 20 members 204 upwardly or downwardly to tilt 25 vertically the conveyor frame 166. As shown in Fig. 14, the screw and nut mechanisms are housed within housings 206 attached to the sides of the conveyor frame 150.

25 A modified form of driving and swinging means for the rear conveyor, together with power operated means for tilting the discharge end of the rear conveyor, is shown in Figs. 17 to 24, inclusive, and herein comprises a sprocket 210 fixed to the power shaft of the motor 8 and connected by an endless chain 211 to a sprocket 212 journaled on and connectable, as by a jaw clutch, to a transversely extending horizontal shaft 213 suitably journaled within 30 the frame 150 of the rear conveyor. Suitably fixed to this shaft 213 are chain sprockets which engage and drive the endless side chains 214 of the rear conveyor. Also suitably fixed to and rotatable with the sprocket 212 is a chain sprocket 215 connected by an endless chain 216 to a sprocket 217 journaled on a transversely extending horizontal shaft 218 likewise suitably journaled within the conveyor frame 150. Fixed to and rotatable with the sprocket 217 is a chain sprocket 219 connected by an endless chain connection 220 to oppositely rotating sprockets 221, 222 suitably mounted on parallel shafts 223, 224 respectively. The sprocket 221 is connectable to the shaft 223 by a jaw clutch 225, and keyed to 40 the shaft 223 is a sprocket 226 connected by an endless chain 227 to a sprocket 228 rotatably mounted on a horizontal shaft 229 herein arranged parallel with the shafts 223, 224 and likewise suitably journaled within the conveyor frame 150. Suitably fixed to the shaft 229 is a worm 230 meshing with a worm wheel 231 keyed to a vertical shaft 232 suitably journaled within the conveyor frame 150, as shown in Fig. 45. Fixed to the lower end of the shaft 232 is a spur gear 233 meshing with the teeth of an arcuate gear segment 234 fixed to the annular roller guiding frame 235 by which the rear conveyor frame is guided for horizontal swinging movement relative to the main frame of the machine. The chain sprocket 222 is connectable to the shaft 224 by a jaw clutch 236, and keyed to this shaft 224 is a chain sprocket 237 connected by an endless chain 238 to a sprocket 239 rotatably mounted on the projecting end of a 50 horizontal shaft 240 herein arranged parallel with and in the rear of the shaft 229 and likewise suitably journaled within the conveyor frame 150. Driven by the sprocket 239 is a sprocket 241 connected by an endless chain 242 55 to a sprocket 243 herein formed integral with at its opposite ends to the clutches 244, 245. It

the chain sprocket 228 and likewise rotatably mounted on the projecting end of the shaft 229. Splined to the shafts 228, 240 respectively are jaw clutches 244 and 245 for connecting the sprockets 241, 243 directly to the shafts. It will thus be seen that when the clutch 225 is connected and the clutch 236 is released, the shaft 229 may be rotated in one direction, and as a result the rear conveyor may be swung horizontally in one direction. When the clutch 225 is released and the clutch 236 is connected, the rear conveyor may be swung in the reverse direction through the chain connections 242, 243. The worm gearing 230, 231 is of the self-locking type and locks automatically, when the clutches 225, 244 are released, the rear conveyor against swinging movement.

5 The improved power operated mechanism for tilting the rear conveyor frame 166 in a vertical direction to vary the elevation of the discharge end thereof comprises helical gears 246, 246 fixed to the shaft 240 and meshing with helical gears 247, 247 rotatable about parallel vertical axes and suitably journaled within the conveyor frame 150. The hubs of these helical gears 247 are internally threaded at 248 and engage parallel vertical screws 249. As shown in Fig. 24, the screws 249 are transversely notched at 250 to receive a transversely extending rod 251 engageable with the lower surface of an angle member 252 secured to the tiltable conveyor frame 166. It will thus be seen that when the sprocket 241 is connected to the shaft 240 by the jaw clutch 245 and the clutch 225 is connected, the adjusting nuts may be rotated relative to the non-rotatable adjusting screws through the chain connections 227, 242. If it is desired to rotate the adjusting nuts in the reverse direction to effect reverse tilting of the conveyor frame 166, the jaw clutch 225 is released and the jaw clutch 236 is connected. At this time the rear conveyor is tilted through the chain and sprocket connection 231, 238, 239.

20 The improved mechanism for controlling the jaw clutches 225, 236, 244 and 245 will now be described. Engaging the jaw clutches 225, 236 respectively are shipper yokes 253, 254 secured to an inclined shaft 255 rotatably mounted within the conveyor frame 150. The shipper yokes are so arranged on the shaft 255 that when one is connected, the other is released. Fixed to the shaft 255 is a crank 256 connected by a link 257 to a member 258 mounted on a transverse operating rod 259 and secured against axial movement relative to the rod and by stop collars 260. Secured to the outer end of the rod 259 is a member 261 externally grooved at 262, and projecting within this groove is an arm 263 of a member 264 secured to a longitudinally extending operating rod 265. Fixed to the forward end of the rod 265 is an operating handle 266. It will thus be seen that when the rod 265 is rotated, the rod 259 is moved axially through the connections 261, 264, and as a result, the rod 255 is locked through connections 256, 257 to connect one or the other of the jaw clutches 225, 226. The member 261 is provided with a depending lug 267 slotted at 268 to receive a projection 269 on the member 264 so that when the rod 265 is moved axially, the rod 255 is rotated. 30 Fixed to the rod 255 is a crank 270 having a depending arm connected by a link 271 to an arm 272 of a lever 273 pivoted to swing about a vertical axis at 274. The lever 273 is connected 35 to its opposite ends to the clutches 244, 245. It

40

45

50

55

70

75

will thus be seen that when the rod 255 is rotated, the lever 273 is swung through the connections 270, 271, 272, and as a result, one or the other of the jaw clutches 244, 245 is connected. To insure an action of one or the other of the clutches 225, 236 prior to the connection of the clutches 244, 245, there is formed in a bracket 275 an H-shaped slot 276. When the handle 266 is in the position shown in Fig. 22, 10 all of the clutches are released, but when the handle 266 is swung upwardly from the full line position shown in Fig. 22 to the dotted line position, the rod 265 is turned, thereby reciprocating the rod 259 and rotating the rod 255 to connect 15 one or the other of the jaw clutches 225, 236. The handle 266 is then in the upper slot of the H and may then be shifted back and forth in a longitudinal direction to reciprocate the rod 265, thereby to rotate the rod 259 and to connect 20 one or the other of the clutches 244, 245. When the handle is swung from the upper position shown in Fig. 22 downwardly to the lower dotted line position, the other jaw clutch 225, 236 is connected and the handle 266 is then in the lower 25 slot of the H and may be shifted longitudinally to connect one or the other of the clutches 244, 245. It will therefore be evident that one of the clutches 225, 236 is always connected prior to the connection of the clutches 244, 245.

30 In the use of the improved loading machine, the machine is propelled forwardly along the mine trackway at a transport speed through the planetary transmission mechanism 16, 17, 21 driven by the motor 9 and controlled by the 35 brake band 27. To effect reversal of the machine along the trackway the brake band 27 is released, and the brake band 35 is applied, and as a result, the machine is propelled in the reverse direction through the transmission mechanism 28, 29, 32 driven by the motor 9. During 40 movement of the machine about the mine, particularly when traveling along an inclined trackway, the support wheels of the machine may be braked by suitably applying the brake band 36.

45 During transport of the machine about the mine, the gathering conveyor 4 and its associated gathering mechanism 6 are held in an elevated position above the tops of the track rails, and when the working place is reached, the adjusting 50 mechanism 139, 140, 142 is suitably operated to tilt the front conveyor downwardly to position the gathering mechanism in its operative position adjacent the mine floor. The clutches controlling the gathering mechanism and the 55 front and rear conveyors are then connected, thereby rapidly circulating the conveyor chains in their guides and moving the gathering chains in their orbits. When the parts are thus disposed, the machine is fed bodily along the mine trackway under the control of the brake band 27 of the planetary mechanism 16, 17, 21 at a 60 loading speed, thereby forcing the material gathering means into the material to be gathered. The gathering chains 75 penetrate and move the material onto the shovel 10 from which the material is received by the front elevating conveyor 4. The material is discharged from 65 the elevating conveyor onto the rear discharge conveyor 5 which in turn discharges into the waiting mine car placed beneath the discharge end of the rear conveyor. The gathering conveyor and its associated elevating mechanism may be swung horizontally in one direction or the other to change their loading position simply by connecting one or the other of the reverse 70 75

frictions 106, 118 controlled by the lever 127, the front conveyor being swung through the connections driven by the motor 7. The rear discharge conveyor may be swung horizontally in one direction or the other simply by connecting 5 one or the other of the jaw clutches 174, 188 controlled by the lever 198, the rear conveyor being swung through the connections driven by the motor 8. The discharge end of the rear conveyor may be tilted vertically by suitably 10 adjusting the hand wheels 200 of the screw and nut elevating mechanism 201, 203 or through the power operated connections 248, 249 driven by the motor 8 and controlled by the clutches 225, 236 operated by the control handle 266. It 15 will thus be seen that the front conveyor and its associated gathering mechanism may be swung in a vertical direction to vary the elevation of the gathering mechanism relative to the material to be loaded, and that the front conveyor and gathering mechanism may be swung horizontally into different loading positions. It 20 will also be evident that the rear discharge conveyor may be swung horizontally in either direction and that the rear discharge end of this 25 conveyor may be adjusted in elevation and the support wheels may be driven to propel the machine forwardly or rearwardly along the mine trackway through the transmission mechanism controlled by the brake bands 27 and 35. By 30 the provision of the three motors 7, 8 and 9, the driving connections for the various mechanisms of the machine have been greatly simplified and the machine has further been simplified by arranging the front and rear conveyors on 35 the main frame of the machine and swiveling the front and the rear conveyors in the manners disclosed, the two conveyors swinging horizontally about a common vertical axis located substantially midway between the truck wheel axes, 40 thereby resulting in an extremely well balanced machine. Further, by the provision of the three motors, it is possible to operate the various mechanisms independently, as desired, with a minimum of handling, and by the provision of 45 the three motors and the elimination of complicated driving connections, it is possible to control all the mechanisms of the machine by the control members 39, 92, 123, 127, 163, 198 conveniently grouped at the operator's side of the 50 machine. It will further be noted that the various mechanisms of the machine are driven through friction safety clutches which release automatically when any of the mechanisms are overloaded, thereby eliminating the possibility 55 of breakage of the parts. By the arrangement of the improved gathering devices at the opposite sides of the shovel 10 at the forward end of the front conveyor, the material to be gathered is penetrated and moved in an improved manner 60 onto the front conveyor. As the general mode of operation of a machine of the type disclosed is well understood by those skilled in the art, and as the mode of operation of the various mechanisms of the improved machine have been 65 clearly described above, further description of the method of operation of the machine is thought unnecessary.

While there are in this application specifically described one form and a modification thereof 70 which the invention may assume in practice, it will be understood that this form and modification thereof are shown for purposes of illustration and that the invention may be modified and embodied in various other forms without 75

departing from its spirit or the scope of the appended claims.

What I claim as new and desire to secure by Letters Patent is:

5. 1. In a loading machine, a wheel mounted base adapted to run along a trackway, a cylindrical frame on said base of a diameter approximating the width of said base, said frame arranged on said base intermediate the truck wheel axes and projecting upwardly from the base, and conveying means including front and rear conveyors swivelly mounted at their adjacent ends on said cylindrical frame and entirely supported by said base, said conveyors swingable horizontally on said frame relative to said base each independently of the other about a common vertical axis coincident with the cylindrical frame axis.
2. In a loading machine, a wheel mounted base adapted to run along a trackway, a cylindrical frame on said base of a diameter approximating the width of said base, said frame arranged on said base intermediate the truck wheel axes and projecting upwardly from the base, and conveying means including front and rear conveyors swivelly mounted at their adjacent ends on said cylindrical frame and entirely supported by said base, said conveyors swingable horizontally on said frame relative to the base each independently of the other about a common vertical axis coincident with the cylindrical frame axis, said conveyors also mounted on said frame for independent vertical tilting movement relative to said frame and base.
3. In a loading machine, a wheeled truck adapted to travel along a mine trackway, a cylindrical frame mounted on said truck midway between the truck wheel axles, coaxial annular frames mounted in superimposed relation on said cylindrical frame for independent rotation about a common vertical axis, conveyor frames connected to said annular frames respectively to swing horizontally therewith about said vertical axis and for independent tilting movement relative thereto, the adjacent ends of said conveyor frames arranged in vertically spaced overlapping relation, with the axes of tilting movement arranged in a vertical plane including said vertical axis.
4. In a loading machine, a portable base, a cylindrical frame supported on said base, an annular frame swivelly mounted on said cylindrical frame, a coaxial relatively rotatable annular frame swivelled on said cylindrical frame, and conveyor frames carried by said annular frames respectively, said conveyor frames also being pivotally connected to said annular frames to swing in a vertical direction relative thereto about horizontal axes lying in a vertical plane including the axes of said annular frames.
5. In a loading machine, a portable base, a cylindrical frame mounted on said base and projecting upwardly therefrom, relatively rotatable annular frames mounted in superimposed relation on said cylindrical frame for independent rotation relative thereto about aligned vertical axes, one of said annular frames surrounding said cylindrical frame, conveyor frame portions mounted on said annular frames respectively for independent tilting movement relative thereto about vertically spaced horizontal axes, said conveyor frame portions being swingable horizontally with said annular frames relative to said base, each of said conveyor frame portions having an end portion mounted on said
- horizontally swingable frame portion for tilting movement in a vertical direction relative thereto, and an endless conveyor guided on the horizontally swingable frame portion and tilttable end portion of each conveyor.
6. In a loading machine, a portable base, a cylindrical frame mounted on said base and projecting upwardly therefrom, relatively rotatable annular frames mounted in superimposed relation on said cylindrical frame for independent rotation relative thereto about aligned vertical axes, one of said annular frames surrounding said cylindrical frame, conveyor frame portions mounted on said annular frames respectively for independent tilting movement relative thereto about vertically spaced horizontal axes, said conveyor frame portions being swingable horizontally with said annular frames relative to said base, each of said conveyor frame portions having an end portion mounted on said horizontally swingable frame portion for tilting movement in a vertical direction relative thereto, and an endless conveyor guided on the horizontally swingable frame portion and tilttable end portion of each conveyor, the adjacent ends of said horizontally swingable conveyor frame portion being arranged in vertically spaced overlapping relation and the axes of vertical tilting movement of said horizontally swingable conveyor frame portions lying in a vertical plane including the axes of said annular frames.
7. In a loading machine, a portable base, a cylindrical frame mounted on said base and projecting upwardly therefrom, relatively rotatable annular frames mounted in superimposed relation on said cylindrical frame for independent rotation relative thereto about aligned vertical axes, one of said annular frames surrounding said cylindrical frame, conveyor frame portions mounted on said annular frames respectively for independent tilting movement relative thereto about vertically spaced horizontal axes, said conveyor frame portions being swingable horizontally with said annular frames relative to said base, each of said conveyor frame portions having an end portion mounted on said horizontally swingable frame portions for tilting movement in a vertical direction relative thereto, and an endless conveyor guided on the horizontally swingable frame portion and tilttable end portion of each conveyor, motor operated devices between said base and each horizontally swingable conveyor frame portion for independently swinging said horizontally swingable conveyor frame portions with said annular frames horizontally relative to said base.
8. In a loading machine, a portable base, a cylindrical frame mounted on said base and projecting upwardly therefrom, relatively rotatable annular frames mounted in superimposed relation on said cylindrical frame for independent rotation relative thereto about aligned vertical axes, one of said annular frames surrounding said cylindrical frame, conveyor frame portions mounted on said annular frames respectively for independent tilting movement relative thereto about vertically spaced horizontal axes, said conveyor frame portions being swingable horizontally with said annular frames relative to said base, each of said conveyor frame portions having an end portion mounted on said horizontally swingable frame portion for tilting movement in a vertical direction relative thereto, and an endless conveyor guided on the horizontally swingable frame portion and tilttable end portion

of each conveyor, the adjacent ends of said horizontally swingable conveyor frame portions being arranged in vertically spaced overlapping relation and the axes of vertical tilting movement of said horizontally swingable conveyor frame portions lying in a vertical plane including the

axis of said annular frame, and the axes of tilting movement of said tiltable end portions being arranged on said horizontally swingable conveyor frame portions remote from the axes of vertical tilting of the latter.

ANDREW HAUGE.
